UNITED STATES PATENT OFFICE.

GEORGE T. PEARSONS, OF NEW YORK, N. Y.

FIRE-EXTINGUISHER.

1,323,992.

Specification of Letters Patent.

Patented Dec. 2, 1919.

Application filed July 1, 1916. Serial No. 107,025.

To all whom it may concern:

Be it known that I, GEORGE T. PEARSONS, a citizen of the United States, residing in the borough of Manhattan, in the city, county and State of New York, have invented new and useful Improvements in Fire-Extinguishers, of which the following is a specification.

This invention relates to fire extinguishers of the type in which a fire extinguishing liquid contained in a tank or reservoir is discharged therefrom by gas pressure generated in a generator in the tank produced by the reaction of the admixing 10 of gas generating materials normally maintained in a separated condition in the tank and free from the liquid in the tank, and it is an object of the invention to provide improved means to maintain the gas generating 15 materials in a separated condition in the generator in the normal and inoperative position of the extinguisher.

It is a further object of the invention to provide improved means to at all times 20 connect the outlet of the reservoir with the liquid in the lowermost part of the reservoir no matter in what position the outlet 25 of the reservoir may be.

In this type of fire extinguisher the expelling agent or gas is generated by the admixing of gas generating materials normally held in a separated condition in a generator in the reservoir, the said generator having an outlet leading into the reservoir 30 usually closed by a spring check valve 35 opening outward from and closing into the generator, and to prevent leakage of the fire extinguishing liquid from the reservoir, the reservoir outlet is also usually provided 40 with a spring check valve opening into and closing outward from the reservoir. The use of such check valves is objectionable as corrosion takes place between the valve and its seat with the result that the 45 valve becomes fixed to its seat, or it is not readily unseated, by the pressures within the reservoir when it is desired to use the same. It is a further object of the invention to obviate the necessity of check valves 50 and to secure a fragile leaf to the outlets of the generator and reservoir to seal the same, this leaf being of such a nature as to prevent leakage of the liquid from the reservoir outlet in the normal condition of the

extinguisher and prevent entrance of the liquid into the generator through the generator outlet, but it will be readily punctured or ruptured by any undue pressure in the generator or reservoir to open the outlets.

In the drawing accompanying and forming 60 a part of this specification Figure 1 is a sectional side elevation of a fire extinguisher showing an embodiment of my invention.

Fig. 2 is a perspective view; partly in 65 section, of the outlet means for the generator with the sealing means applied thereto; and

Fig. 3 is a sectional detail of the outlet 70 means for the reservoir.

Similar characters of reference designate like parts throughout the different views of the drawing.

In the drawing I have shown an embodiment of my invention in connection with a 75 fire extinguisher of the type in which the extinguisher is set in operation by inverting the extinguisher, in which there is provided a reservoir for a fire extinguishing liquid, such as carbon tetrachlorid, preferably consisting of a cylindrical body portion 4 closed at one end, to constitute the top, by a head 5 fixed to the body portion and having an opening closed by a removable cover 6 having an inwardly extending 80 projection 16, and a bottom 7 fixed to the body portion 4 to close said end and preferably constructed in the form of a standard upon which to support the extinguisher.

The fire extinguishing liquid is expelled 85 from the reservoir by a suitable agent, such as a gas generated by means in a generator in the reservoir, consisting of a receptacle 8 having screw threaded connection with the cover 6 to close and suspend the receptacle in the reservoir. The lower end of the receptacle is cone-shaped and has an outlet tube 9 leading into the reservoir.

A receptacle 10 having an open upper 90 end for a gas generating material is supported in the receptacle 8 at a point adjacent the juncture of the cone-shaped portion with the body of the receptacle 8 to provide a space between the bottoms of the two receptacles. The receptacle 10 is of 95 less width than the receptacle 8 to provide a space between the lateral walls of the receptacles, and the receptacle 10 is main-

tained centrally by laterally projecting lugs 13 abutting against the inner side of the receptacle 8.

A third receptacle 14 of fragile material, such as glass, and entirely closed, for another gas generating material, such as sulfuric or hydrochloric acid, is supported in the receptacle 10 and has an annular contracted and thinned portion, as at 15, adjacent to the bottom of said receptacle, but which in use will be uppermost in the normal position of the extinguisher, as shown. The receptacle 10 has an inwardly extending flange 17 to coöperate with the contracted portion of the bottle 14 for a purpose to be hereinafter described. The receptacle 10 above the receptacle 14 is supplied with the other gas generating material, such as bicarbonate of soda. In operation, as stated, the extinguisher is inverted when the bicarbonate of soda will fall into the upper part of the receptacle 8, and the bottle 14 will drop and the end or bottom with the contracted and thinned portion will strike against the cover projection 16, the impact of the receptacle 14 against said projection breaking said receptacle at the thinned portion when the acid will flow therefrom and admix with the bicarbonate of soda, reacting and generating a gas, such as carbonic acid gas, said gas passing through outlets 10' in the receptacle 10 and up between the walls of the latter receptacle and the receptacle 8 and is expelled through the outlet tube 9 in the reservoir to create pressure therein and expel the fire extinguishing liquid.

To filter and render the generated gas anhydrous or dry and non-acid, a suitable material is placed in the cone-shaped portion of the receptacle 8 through which the gas passes, the said material absorbing or neutralizing any moisture or acid in said gas. A screen 12 may be provided at the juncture of the cone-shaped portion with the body of the receptacle 8, which may serve as the support for the receptacle 10 and which prevents the filtering material from dropping onto the reacting materials in the upper portion of the generator when the extinguisher is inverted. To prevent the gas from expelling any of the absorbing or acid neutralizing material through the outlet tube 9 and from choking said tube the inner end of the tube is closed and the lateral walls perforated. The bottle 14 is made of a size to readily clear the annular flange 17. However, should the extinguisher be supported on its side said flange will engage in the contracted portion of the bottle 14 and prevent the bottle from sliding and abutting against the cover projection 16 and the consequent breakage thereof.

To maintain the gas generating and absorbing materials in the generator free from

the liquid in the tank or reservoir the open end of the tube 9 is sealed and closed by a suitable material which will prevent the liquid in the reservoir from entering said tube, but which will be readily punctured or ruptured by the gas generated in the generator when said gas attains a predetermined pressure and permit said gas to enter into the reservoir. This seal and closure consists of a leaf 17' of fragile material, such as tin foil or the like, secured and carried between a pair of washers 18, 19 removably connected to the tube 9 by a perforated cap 20.

This type of fire extinguisher is set in operation by merely inverting the extinguisher. However, in use it invariably happens that the extinguisher is held with the discharge outlet in different positions, and to permit of this universal use of the extinguisher, means are provided to at all times connect the discharge outlet of the reservoir with the liquid in the lowermost part of the reservoir. For this purpose the reservoir outlet is located in a tubular portion 21 in the bottom to which is connected a nozzle 22 extending laterally and through an opening in the bottom of the 7. To connect said outlet at all times with the liquid in the lowermost part of the reservoir I secure in said outlet a flexible metallic intake, such as is commonly termed "flexible metallic hose". This intake consists of a portion 23 fixed to the outlet 21. Connected to the tube 23 by a coupling 24 are flexible metallic tubes 25, 26, similar to the tube 23, with the free or intake ends lying adjacent the side and opposite ends of the reservoir. The coupling 24 will be of sufficient weight to flex the tube 23 to cause the tubes 25, 26 to lie adjacent the sides of the reservoir. The tube 23 is also sufficiently flexible to permit the coupling with the connected tubes 25, 26 to be swung and oscillated about the outlet 21 as axis, and when the extinguisher is in an upright position the ends of the tubes 25, 26 will assume a position adjacent the top and bottom of the reservoir.

It is essential that when the extinguisher is in an inverted position that communication between the tubes 26 and 23 be shut off, otherwise the gas will be expelled through said tubes and will not exert any force upon the liquid in the reservoir to expel the same, or that the tube 25 be shut off from the tube 23 should the extinguisher be restored to an upright position for the same purpose. To shut off the tubes 25 and 26 from the tube 23 and to connect either of them thereto when the extinguisher is either in an upright or inverted position, valve mechanism is provided consisting of a pair of valves 27 and 28 connected by a rod 29 coöperating with valve seats 30, 31 at opposite ends of the coupling 24.

To prevent the weight of the coupling 24

and tubes 25, 26 from flexing the tube 23 too greatly with the result that the tubes 25, 26 would engage with the top or bottom of the reservoir, depending upon the position 5 of the extinguisher and shutting off the flow of the liquid thereinto, and to guide the tubes and permit them to assume variable positions adjacent the side of the reservoir and about the longitudinal axis 10 of the reservoir there is provided a pair of annular guide rails 34, 35 carried by supporting rods 36, 37, these guides engaging with the curved portions of the coupling 24 adjacent to where it is connected to the tube 15 23. Further guide rails 34' and 35' are provided for the engagement of the tubes 25, 26 at a point between the ends.

Leakage and evaporation of the fire extinguishing liquid through the outlet nozzle 22 is prevented by a leaf seal 32, similar to the seal 17' for the generator outlet, 20 removably connected to the nozzle by a perforated cap 33.

Having thus described my invention I

25 claim:—

1. In a fire extinguisher, the combination with a reservoir having an outlet, of an intake for the reservoir outlet comprising flexible metallic tubing connected to the outlet 30 having inlets in free ends lying adjacent opposite ends, and means to maintain the free ends adjacent the side of the reservoir and permit said free ends to assume different positions, substantially as and for the purpose 35 specified.

2. In a fire extinguisher, the combination with a reservoir having an outlet in one end, of an intake for the reservoir outlet comprising a flexible tube secured to the outlet, 40 and flexible metallic branch tubes connected to the first tube with their ends lying adjacent the side and opposite ends of the reservoir; and an annular guide for said branch tubes, substantially as and for the purpose 45 specified.

3. In a fire extinguisher, the combination of a reservoir for a fire extinguishing liquid having a discharge outlet and an opening in the said reservoir; a removable cover for the 50 opening having an inwardly extending projection; and a generator comprising a receptacle suspended in the reservoir from the cover to carry a dry gas generating material and having an outlet leading into the reservoir, and a second receptacle of fragile material for an acid movably supported in the first 55 receptacle and adapted to come in contact with the cover projection when the extinguisher is inverted, said receptacle having an annular contracted and thinned portion adjacent one end, substantially as and for the purpose specified.

4. In a fire extinguisher, the combination of a reservoir for a fire extinguishing liquid 60 having a discharge outlet and an opening

in said reservoir; a removable cover for the opening having an inwardly extending projection; a receptacle suspended in the reservoir having an outlet leading into the reservoir; an open end receptacle for a gas 70 generating material supported in the first receptacle; a sealed fragile receptacle in the open end receptacle to contain another gas generating material free from the first gas generating material, said latter receptacle 75 adapted to assume a position in the lower part of the open end receptacle in the upright position of the extinguisher and to abut against the cover projection when the extinguisher is inverted to rupture said receptacle and said first receptacle suspended from the cover being arranged to carry another material between the open end receptacle and the outlet of the first receptacle through which the gas is passed before it 80 passes into the reservoir substantially as and for the purpose specified.

5. In a fire extinguisher the combination of a reservoir to contain a fire extinguishing liquid having a discharge outlet; and a gas 90 generator, comprising a receptacle for a gas generating material suspended in the reservoir having an outlet leading into the reservoir, an abutment extending into said receptacle, and a second receptacle of fragile material to contain another gas generating material movably supported in the first receptacle, said receptacle adapted to assume a position in the lower part of the first receptacle in the upright position of the extinguisher and to come in contact with the abutment when the extinguisher is inverted, substantially as and for the purpose 95 specified.

6. In a fire extinguisher the combination 105 of a reservoir to contain a fire extinguishing liquid and having a discharge outlet; a receptacle to contain a gas generating material suspended in the reservoir having an outlet leading into the reservoir; an abutment extending into said receptacle; a sealed fragile receptacle movably supported in the first receptacle to contain a gas generating material in a separated condition and free from the material in the first receptacle, said 110 sealed receptacle being adapted to assume a position in the lower part of the first receptacle in the upright position of the extinguisher and to come in contact with the abutment when the extinguisher is inverted, substantially as and for the purpose specified.

7. In a fire extinguisher the combination 120 of a reservoir to contain a fire extinguishing liquid and having a discharge outlet; a receptacle to contain a gas generating material suspended in the reservoir having an outlet leading into the reservoir; an abutment extending into said receptacle; a sealed fragile receptacle movably supported in the first receptacle to contain a gas generating mate- 125

130

rial in a separated condition and free from the gas generating material in the first receptacle, said sealed receptacle being adapted to assume a position in the lower 5 part of the first receptacle in the upright position of the extinguisher and to come in contact with the abutment when the extinguisher is inverted to break said receptacle

to release the gas generating material therein; and means to connect the reservoir outlet with the liquid in the lowermost part of the reservoir in all positions of the extinguisher, substantially as and for the purpose specified. 10

GEO. T. PEARSONS.
